UNITED STATES PATENT OFFICE

2,427,332

ADJUSTABLE SUPPORT FOR INDUCTION COILS

Harold A. Strickland, Jr., Detroit, Mich., assignor, by mesne assignments, to The Budd Company, Philadelphia, Pa., a corporation of Pennsylvania

Application September 18, 1941, Serial No. 411,297, now Patent No. 2,365,021, dated December 12, 1944, which is a division of application Serial No. 384,503, March 21, 1941, now Patent No. 2,408,350, dated September 24, 1946. Divided and this application July 22, 1943, Serial No. 495,701

8 Claims. (Cl. 175—359)

1

My invention relates to furnaces for heating by electromagnetic induction, and particularly to those which can be used or are intended for use in the heating of bar or billet stock for forging purposes. In such furnaces, bar or billet stock of either solid or tubular form, and either circular or angular in cross-section, is inserted within a coil adapted to be supplied with power from an alternating current source, usually a high-frequency alternating current source of considerable voltage, and the power being turned on to the coil, heating currents are set up within the mass of the bar or billet to be heated due to the electromagnetic induction from the coil itself. These currents heat the bar or billet to a forging temperature. Such a bar or billet is commonly called a workpiece.

An object of my invention is to provide means for supporting the induction heating coil of the furnace in firm and stable relationship to the other parts of the furnace. An additional object is to provide a coil support which may be adjusted readily with reference to the furnace door and push-out rod. Still other objects are to provide a coil support which requires a minimum of parts and space for installation, which is readily accessible for adjustment, which holds the coil with a yielding pressure; and which permits complete removal of the coil without structural disorganization.

Other objects will appear on consideration of the accompanying drawings in which:

Figure 1 is a side elevation of the machine of my invention with the principal parts enclosed by the housings of the machine. The heating coil is shown in dotted line in the upper portion of the housing, while the door normally closing the lower part of the housing, has been removed to show a bank of condensers connected with the coil;

Figure 2 is a vertical section on the axis of the heating coil, showing the heating coil and its immediate mounting and housing the remaining portions of the machine being broken away;

Figure 3 is a transverse section, transaxial to the heating coil, taken on line 3—3 of Figure 2 looking in the direction of the arrows;

Figure 4 is a perspective view of a bridge-piece connected with a heating coil support clamp; and

Figure 5 is a transaxial segmental section showing the bridge-piece of Figure 4 in use in connection with a special heating coil.

Referring now to the drawings, it will be observed that I have made the frame and housing of the furnace machine 30 generally of L-shape

2

as viewed in side elevation, and in form not unlike the operator's switchboard of a manually-operated telephone system. This is to say that the frame and housing comprise a horizontal branch 31 having a horizontal table-like top 32, and a vertically extending portion 33. I shall not go into the details of frame members and panelings of this frame and housing 30 further than to say that it is constructed of metal of a strength adequate to support the parts which I show and describe as supported thereby and housed therein. Front, side and back door openings 34, 35, and 36 (the latter not shown in form, although it is intended to extend the full length 15 of the back of the housing 30) are provided for ready access to the various instrumentalities supported by and housed within the casing 30, and these openings are provided with suitable closures such as that 37 shown in the door opening 20 34 of the front of the casing, which closures may be provided, as is common, with suitable hinges and locks for ready manipulation and locking. An opening 38 in the top 32 of the table-like portion 31 is closed by a cast foundation member 39 which mounts the heating coil 40. An opening 41 in the lower section of the vertical portion 33 of frame 30 is closed by a backplate 42 which mounts the workpiece gauging and ejecting mechanism and the magnetic core of the coil. A front-plate 50 rising from the region of the foundation plate 39, coacts with the rear-plate 42 in supporting the hood 47. The front plate closes the otherwise open front end of the hood 47. The foundation plate 39, the coacting and surmounted 35 back and front plates 42 and 50 (also castings preferably) and the hood 47 together constitute a housing unit individual to the heating coil 40 and its immediate appurtenant parts. The front plate 50 is provided with an opening 51 through 40 which the workpieces are fed to the furnace by projecting them axially of the coil 40. A hinged door 52 closes or shrouds this opening during the heating operation.

The heating coil 40 is formed of hollow conductors 61 preferably of square shape in cross section. Through these coils cooling water in sufficient volume to cool the coil is passed. Individual turns of the coil are electrically insulated from each other.

Both top and bottom sides of the coil are provided with insulating layers. On the inner side are a plurality of axially extending segments of fire brick 75 which are retained in position in the coil by a plurality of intermediate tubular rails 76, these rails also being provided with brick

securing clips or plates 79 which engage the edges of the bricks to retain them in position.

The outer surface of the coil is covered with segmental strips 69 which together completely encase the outer periphery of the coil, protecting the same and providing heat and electrical insulation.

The rails 76 are supported in position within the coil by means of end attachment devices comprising outwardly and radially extending supporting studs 83 secured to the ends of the rails 76 which project beyond the ends of the coil 40.

These studs are passed respectively through slots or holes, as may be preferred, in the outer ends of metal or insulating material, rails 84 laid longitudinally over the length of the exterior of coil 40 to project slightly beyond each end. As shown, the rails are of channel cross-section to afford less generation of eddy currents as well as lightness with strength. As the opposite end (the left-hand end, as shown) the projecting ends of work-supporting rails 76 are engaged within the loops 85 of screw-hooks 86, the threaded outer ends of which are carried radially through apertures or slots in the opposite ends of the rails 84, there being preferably, though not necessarily, one securing rail 84 for each work-supporting rail 76. When the nuts 87, respectively, on the ends of studs 83 and screw-hooks are tightened up, they hold the outer ends of the rails 76 toward or against the inner surface of the mica cylinder 66 as does the expanding ring 89. Thus the rails 76 are held in position throughout their length and firmly hold the firebrick lining 75 in place. There may be provided as many expanding rings 80 as are needful to meet the requirements of coil length.

Heating coil 40 with its workpiece-supporting appurtenances is mounted with its axis coinciding with a general horizontal axis A—A of the furnace machine, by supporting it from coil centering C-clamps 98 carried from and forming a part of pedestals 99 erected upon and secured to the cast foundation plate 39 of the table-portion 32 of the housing. There are two (or more in case of large coils) of these coil-supporting pedestals 99 spaced apart an adjustable distance to support coils of a number of different axial lengths without relocation upon the foundation plate 39. Reference particularly to Figures 2 and 3 will make clear their construction. The lower portion of the pedestals 99 has a plane of symmetry coincident with the vertical plane of the axis A—A upon which the coil 40 is to be centered. It terminates a considerable distance below the axis A—A, a distance sufficient to permit the accommodation of coils 40 of a number of different sizes. It is provided with integrally-formed right and left branches 100, 101 making equal angles with the vertical plane V—V of axis A—A. Threaded through the arms 100, 101 on radial lines intersecting axis A—A are radially adjustable coil supporting studs 102, 103. The heads of these studs 102, 103 are located toward coil 40 from the arms 100, 101 and support the coil directly upon pads of insulating material 104 secured to the heads. Thus by relatively adjusting studs 102, 103 the axis of a coil 40 of any accommodatable diameter may be placed directly upon the horizontal axis A—A of the furnace machine. In this case there is provided only one securing bar 84 for two rails 75, the two rails being bridged together and to the bar 84 by lateral extensions having a rigid insulated connection with bar 84 and taking at their op-

posite ends the studs 83. Thus there is space for pads 104 directly to engage the coil, and more importantly rails 76 may be removed while the coil 40 is yet firmly clamped in position.

The C-clamps 98 of these supporting pedestals are comprised of C-arms, as clearly appears in Fig. 3, forked at their lower ends 105 to straddle the lower portions of pedestals 99 and be pivoted at 106 on the opposite side of the vertical plane V—V from the body of the C-clamp. When the clamps 98 are in clamping position, their upper ends 107 lie in the vertical plane V—V, and are provided with a threaded adjusting stud 108, the head 109 of which lies toward the coil 40 from the upper end 107 with the axis of the stud in the vertical plane V—V. A set screw 98a acting against a stop surface on the base arm 100 limits the upward movement of the clamp 98.

Beyond the head 109 projects a reduced extension of the stud 112 on which is radially slidably mounted a bridge member 113 carrying at its opposite ends pads of insulating material 113a. A spring 110 on the reduced section 112 and intermediate head 109 and bridge 113, presses the bridge toward the coil 40 to achieve yieldingly the clamping of it, while a washer and cotter 111 prevent the radially movable bridge from dropping from the reduced extension of the stud 112 when the clamp is released.

This clamping arrangement is not only adapted for clamping the coils of different diameters merely through the radial adjustment of stud 108, but also to clamp under different pressures through the adjustment of spring 110. Yet further, however, the structure of bridge member 113 is such that merely by rotating it on the reduced extension 112 of stud 108, it is adapted to engage with the top of one of the rails 84 instead of engaging between rails 84. See Figures 40 and 6 in this connection. Examination of these will show that pads 113a are elongated and provided in their middles with slots 113b of a dimension adapting them to fit over the top of a rail 84 when bridges 113 are rotated ninety degrees 45 from the position shown in Figure 3. Thus coils having any desired arrangement of bars 84 may be used, and the smaller coils in which there are but three or four rails 76 and accompanying bars 84 may be accommodated as readily as the larger ones.

The foundation plate or base 39 upon which the coil 40 is mounted through the pedestals 99 is, as has been said, a casting in this embodiment of the invention. It is formed with its upper face 121 on either side of the pedestals, slightly downwardly and inwardly inclined toward the vertical plane V—V whereby collected foreign matter or moisture will gravitate toward the center of the plate from both sides and from each end, the ends being similarly inclined. At the center of the plate and surrounding the region of mounting of the pedestals in an endless groove 122 which keeps moisture away from the pedestals and prevents its creeping upon them. The center of the casting is thus a pad 123 upon which the pedestals are mounted. Groove 122 communicates at its axially inner end with a drainage conduit 124 suitably connected to a drain, as will hereinafter appear. The under-margins 125 of base 39 are finished to rest upon the top of table 32 and be secured thereto by suitable bolts. The sides 126 are also finished and receive in overlapping relation the lower edges of the hood 47 secured thereto by suitable cap screws. These and no other screws are

removed when it is desired to remove the hood and front plate assembly. The ends 121 of the plate receive in overlapped relation and bolted thereto if desired (bolts not shown), the end plates 42 and 50, thereby vertically aligning them with respect to the base 39.

Devices associated with the feeding-in of the workpieces are mounted in connection with the front plate 50 of the housing of coil 40. Such are the coil mouthpiece 96 and the door 52 and appurtenant instrumentalities. The mouthpiece 96, as has been said, serves to enter the workpieces of bar or rod stock properly upon the axis A—A of the coil 40 and the supporting rails 76. It is by virtue of its susceptibility to removal and replacement from the opening 51, suited in size to the various sizes of coils and stock. It is suitably bolted in place (bolts not shown) and mounted with a clearance 96a for radial adjustment to precise position on axis A—A. On its inner side it is provided with an annular series of axially and inwardly projecting spaced teeth at 135, the inner side walls of which project radially and axially inwardly toward the coil, and the extremities of which have an extent substantially of the same diameter as those circles on which lie the inner edges of the work-supporting fins 88, while their inner sides meet their inner ends at a relatively sharp angle. All this clearly appears in Figure 3. Thereby these teeth guide the stock accurately into engagement with the fins 88 of the supporting rail 76, preventing impingement upon intermediate transversely-extending walls (this through their inclined inner walls and their extremities), and when the workpiece is pushed out, removed from it foreign matter such as light scale which may have formed (this through the sharp innermost edges). Such foreign matter as is removed falls between the teeth or past their inner extremities and upon the hopper plate 186 which discharges through opening 181 to a chute 188 projected from the opening 181 exteriorly of the machine. Thus no scale or other foreign matter drops to the foundation plate 39.

Viewing now the ensemble of all instrumentalities connected with the housing of coil 40, especially with the foundation plate 39 and the front and rear plates 42 and 50 which are erected thereon, it will be seen that all of these instrumentalities can be removed as a unit with the housed coil 40, if this be desired, merely by unbolting the foundation plate 39 and the back plate 42 from the faces of the principal housing 30 of the machine, the electrical, water and other connections having been previously broken. It will, of course, be particularly necessary to remove the bus bar system 53 by disconnection at the connectors 133 and appropriate lowering of the bus bars. This makes for convenient major subassembly and shifting of such major subassembly from machines to test bench or back, or substituting one such major subassemblage from one machine in another, and so forth. Normally, however, the subassembly comprising plate 50, door 52, box 193, and hood 47, is the unit received, leaving base 39 and plate 42 on the main frame. This alone gives four-sided access to the coil 40 as clamped in place.

This application is a division of my copending application Serial Number 411,297, filed September 18, 1941 (now Patent No. 2,365,021, dated December 12, 1944), which is in turn a division of my copending application Serial No. 384,503, filed March 21, 1941, now Patent No. 2,408,350, dated September 24, 1946.

Though only a single form of the invention is

illustrated and described, the invention is not limited thereto but may be embodied in various forms as desired. As various changes in construction and arrangement of parts may be made without departing from the spirit of the invention as will be apparent to those skilled in the art, reference will be had to the appended claims for a definition of the limits of the invention.

I claim:

10. The combination with a coil of a casing therefor, coil supports, said supports comprising at least three members angularly spaced around said coil and radially adjustable with reference to the supported coil, at least one of said members having a contacting element, rotatable with reference to the member and provided with spaced contacts.
15. The combination with a coil, of supports therefor comprising at least three angularly spaced coil supporting members, one of which includes a bridge element slidably mounted on the member and having displaced coil contacts attached thereto and means for yieldably mounting said element at the outer limit of movement on the member.
20. 3. In combination a base, at least two co-acting and fixed support members mounted on said base, a coil mounted on said co-acting support members, and a third support member movable into engagement with said coil, said third member being pivotally mounted on said base on an axis parallel to the coil axis on one side of the coil axis and being of C-shape and provided with coil clamping means on the side opposite its hinge and opposite said fixed supports, whereby the space beyond the coil opposite the base may be opened for coil removal.
25. 4. In combination a base, rigid support elements adjustably mounted on said base, a coil mounted on said support members and a third support member pivotally mounted on said base on an axis parallel to the coil axis on one side of the coil axis and being of C-shape and provided with coil clamping means on the side opposite its hinge and opposite said fixed supports, said third support member having a yieldable contact element movably mounted thereupon.
30. 5. In combination a base, converging support members symmetrically mounted on said base on either side of an intermediate transverse plane of reference, a coil mounted on said converging support members, a third support member mounted on said base and lying in said plane of reference on the side of said coil opposite from said converging support members, said support members being radially adjustable with reference to said coil, and means tending to prevent rotation of said coil when the supports are in normal holding position.
35. 6. A supporting member for induction heating coils and the like comprising a base, converging support members mounted on said base for engagement with a coil of cylindrical contour, a third support pivotally mounted on said base on an axis parallel to the coil axis on one side of the coil axis and being of C-shape and provided with coil clamping means on the side opposite its hinge and opposite said fixed supports and adapted to engage said coil at a point angularly displaced from said converging support members, each of said supports being radially adjustable with reference to the point of convergence of said converging support members all of said supports being mounted on said base at one side of the coil.

7. A support member for induction heating coils and the like, having at least three angularly related support members movable into and out of engagement with a supported coil, a contact element for at least one of said converging supporting members, said contact element comprising a bridge plate rotatably and axially movable on said member, contact pads transversely positioned at the ends of said bridge member and spring means for resiliently maintaining the bridge member at the limit of movement on the support member.

8. A support member for induction heating coils and the like, having at least three angularly related support members movable into and out of engagement with a supported coil, a contact element for at least one of said converging support members, said contact element comprising a bridge plate rotatably and axially movable on said member, contact pads transversely positioned at the ends of said bridge member and spring means for resiliently maintaining the

5
10
15
20

bridge member at the limit of movement on the support member, said pads having transverse recesses formed thereon intermediate the ends thereof.
